UNITED STATES PATENT OFFICE.

WILLIAM A. EDWARDS, OF CHICAGO, ILLINOIS.

FUEL CONVERTER.

Application filed January 16, 1922. Serial No. 529,692.

To all whom it may concern:

Be it known that I, WILLIAM A. EDWARDS, a citizen of the United States, residing at Chicago, in the county of Cook and State of Illinois, have invented certain new and useful Improvements in Fuel Converters, of which the following is a specification.

This invention has reference in general to the conversion of a liquid fuel into a combustible mixture, and while capable of employment in connection with various apparatuses in which liquid fuel is used, it is shown herein for purposes of illustration as applied to an internal combustion engine.

One of the primary purposes of my present invention is to provide a device which will break up and atomize the liquid particles flowing through the fuel passage, and particularly the heavier and less volatile ends of the fuel, which are not completely atomized or vaporized by the action of the carburetor, and also those fuel ends which tend to condense and collect in globular form in the fuel passage as the mixture is traveling therethrough.

For the purpose of facilitating an understanding of my invention, I have illustrated in the accompanying drawings one preferred embodiment thereof from an inspection of which, when considered in connection with the following description, my invention and many of its inherent advantages should be readily understood and appreciated.

Referring to the drawings—

Fig. 1 is a fragmentary view of a gas engine equipped with my invention;

Fig. 2 is a perspective view of a structure embodying my invention; and

Fig. 3 is a sectional view on the line 3—3 of Fig. 1.

Referring to the drawings more in detail, reference character 5 indicates generally an engine block of any preferred construction, usually formed to provide the water jacket 6 surrounding the cylinder 7, and having a combustion chamber 8 to which the fuel is supplied through a passage 9, the flow of fuel being controlled by the intake valve 11 in the usual manner.

The fuel mixture is supplied to the engine through a supply passage 12, formed customarily in the intake manifold 13, which may be of any approved construction.

My invention is designed to be interposed in the fuel passage between the carburetor

(not shown) and the engine cylinder, and while it may be located at any desired point in this passage, it is preferably disposed close to the cylinder, and, in the present instance, is illustrated as located at the junction between the manifold and the engine block.

My invention, as herein illustrated, comprises a tubular member indicated generally by reference character 14 adapted to be inserted and located in the fuel passage, and as shown, is of cylindrical form adapted to snugly fit within the fuel passage, and it is provided adjacent its intake end with an annular rib or flange 15 adapted to fit in the groove 16 customarily formed at the junction of the manifold and the engine block to receive the usual packing sleeve. The tube has a bore which is frusto-conical in shape, the smaller or intake end being disposed toward the carburetor and the larger or delivery end being disposed toward the cylinder. It will be observed that by reason of the increasing thickness of the walls of the tube from the delivery to the intake end thereof, there is provided at the intake end and surrounding the bore a substantially flat face formed by the end wall of the tube which is disposed transversely with respect to the longitudinal axis of the tube.

Those heavier ends of the fuel mixture which, by reason of the fact that the speed of the mixture adjacent the walls is slower than the speed in the center of the stream of the flowing mixture, tend to accumulate upon and adjacent the passage walls, impinge against the face 17 disposed across their path and are thereby prevented from flowing or being carried directly into the cylinder in their non-volatile and non-combustible condition. The air and lighter portions of the mixture will be drawn directly through the tube, and by reason of the reduced cross-sectional area of the intake end of the tube with respect to the cross-sectional area of the passage itself, the speed of the air and mixture will be materially increased at this point, thereby serving to further break up and volatilize those liquid particles carried in the mixture and also such of the heavier particles as may be wiped off of the inner margin of the wall or face 17 by the inrushing mixture. The greater portion, however, of the condensed liquid particles accumulated on the wall 17 will by

100

105

110

capillary action and gravity flow to the lower edge of said wall, from whence they are discharged or delivered through a duct 18 into the throat of the tube, where by reason 5 of the reduced pressure and the higher velocity of the mixture flowing through the tube, these liquid particles are thoroughly broken up and dissipated into the mixture so that they are delivered to the cylinder in 10 combustible condition.

Any extremely heavy ends of the liquids which may not be broken up and thoroughly atomized upon their issuance into the tube from the duct 18, and which may fall 15 by gravity in the passage 9, or be intercepted by and caused to condense upon the inner vertical wall of said passage, will flow to the lowest point of this passage, which is at the delivery end of the tube 14. A 20 duct 19 establishes communication between this point of collection in the passage 9 and the restricted portion of the tube 14, and these accumulated liquids will be drawn, by reason of the differential of pres- 25 sures between the intake and delivery ends of this duct, through the duct, and again delivered into the restricted and low pressure area of the tube, where they are again subjected to the vaporizing and atomizing 30 action of the flowing mixture.

By this construction, therefore, the heavy less volatile liquid portions of the fuel may be repeatedly subjected to a vaporizing and atomizing action, thereby insuring that they 35 will be thoroughly broken up and delivered to the cylinders in combustive condition. Those heavier liquid particles traveling through the mixture passage are first im- 40 pinged against the face 17 and are then de- livered from their point of accumulation into the restricted portion of the tube where they are finally broken up and carried along by the rapidly flowing mixture.

It will be apparent from the foregoing 45 that I have provided a device which is adapted to convert the unvaporized liquid portions of a fuel mixture into a substantially homogeneous mixture capable of rapid and effective combustion which will result 50 in a high efficiency of the engine and a diminution of carbon in the cylinders.

While I have shown and described a preferred embodiment of the invention, the details thereof are obviously capable of considerable modification within the scope of 55 the invention as defined in the following claims.

I claim:

1. The combination with a fuel supply passage, of a tube disposed therein, the exterior of said tube being shaped to fit the walls of said passage and the bore of said tube being of frusto-conical shape, the smaller end thereof being opposed to the flow through said passage, said tube being provided with a duct leading from the passage at the exterior of the tube, to the interior of the tube near the smaller end thereof.

2. The combination with an intake passage of a gas engine, of a tube disposed therein having a bore of frusto-conical shape, the end of the tube surrounding the smaller end of the bore presenting a flat face extending from the bore to the surrounding walls of the passage, said tube being provided with a duct leading from said face to the bore of the tube adjacent the smaller end thereof.

3. A fuel converter, comprising a tube 80 adapted to be disposed in a fuel supply passage, the bore of said tube being tapered from end to end, the minimum cross-section being at the intake end of the tube, the end walls of said tube at the intake end thereof being disposed substantially at right angles to the longitudinal axis of the tube, and a duct establishing communication between the exterior and the interior of said tube at the intake end thereof.

4. A fuel converter, comprising a tube 90 adapted to be disposed in the intake passage of a gas engine and provided with a bore of increasing diameter from the intake to the delivery end thereof, the walls of said tube presenting around the intake end of the bore a substantially flat face disposed in the path of the mixture flowing through the passage, and a duct leading from said face to the interior of the tube 95 adjacent the smaller end of the bore.

5. A fuel converter, comprising a tube 100 adapted to be positioned in the intake passage of a gas engine and provided with a bore tapered from the delivery to the intake end thereof, the smaller end of the bore being surrounded by an annular face opposed to the flow of mixture through said passage, said tube being provided with ducts leading from the exterior of the tube at the ends thereof to the interior of the tube adjacent the smaller end of the bore.

WILLIAM A. EDWARDS.
